The ornamental design for a chess set, as shown and described.

DESCRIPTION

FIG. 1 is a perspective view of the chess piece representing the king;

FIG. 2 is a side view of the king chess piece of FIG. 1;
FIG. 3 is a bottom view of the king chess piece of FIG. 1;

FIG. 4 is a top view of the king chess piece of FIG. 1;
FIG. 5 is a perspective view of a chess piece representing the queen chess piece;

FIG. 6 is a side view of the queen chess piece of FIG. 5;
FIG. 7 is a bottom view of the queen chess piece of FIG. 5;

FIG. 8 is a top view of the queen chess piece of FIG. 5;
FIG. 9 is a perspective view of a chess piece representing the bishop;

FIG. 10 is a side view of the bishop chess piece of FIG. 9;

FIG. 11 is a bottom view of the bishop chess piece of FIG. 9;

FIG. 12 is a top view of the bishop chess piece of FIG. 9;

FIG. 13 is a perspective view of a chess piece representing the knight;

FIG. 14 is a top view of the knight chess piece of FIG. 13;

FIG. 15 is a bottom view of the knight chess piece of FIG. 13;

FIG. 16 is a front view of the knight chess piece as viewed from lines 16—16 of FIG. 14;

FIG. 17 is a side view of the knight chess piece as viewed from lines 17—17 of FIG. 14;

FIG. 18 is a rear view of the knight chess piece as viewed from lines 18—18 of FIG. 14;

FIG. 19 is a side view of the knight chess piece as viewed from lines 19—19 of FIG. 14;

FIG. 20 is a diagonal-side view of the knight chess piece as viewed from lines 20—20 of FIG. 14;

FIG. 21 is a diagonal-side view of the knight chess piece as viewed from lines 21—21 of FIG. 14;

FIG. 22 is a diagonal-side view of the knight chess piece as viewed from lines 22—22 of FIG. 14;

FIG. 23 is a diagonal-side view of the knight chess piece as viewed from lines 23—23 of FIG. 14;

FIG. 24 is a perspective view of a chess piece representing the rook;

FIG. 25 is a side view of the rook chess piece of FIG. 24;

FIG. 26 is a bottom view of the rook chess piece of FIG. 24;

FIG. 27 is a top view of the rook chess piece of FIG. 24;

FIG. 28 is a perspective view of a chess piece representing the pawn;

FIG. 29 is a front view of the pawn chess piece of FIG. 28;

FIG. 30 is a rear view of the pawn chess piece of FIG. 28;

FIG. 31 is a bottom view of the pawn chess piece of FIG. 28;

FIG. 32 is a top view of the pawn chess piece of FIG. 28; and,

FIG. 33 is a side view of the pawn chess piece of FIG. 28.
